UNITED STATES PATENT OFFICE.

WILLIAM FRENCH, OF NEW YORK, N. Y.

KILN FOR BURNING POTTERY-WARE AND OTHER ARTICLES.

SPECIFICATION forming part of Letters Patent No. 233,230, dated October 12, 1880.

Application filed March 4, 1880. (No model.)

To all whom it may concern:

Be it known that I, WILLIAM FRENCH, a subject of the Queen of Great Britain, residing at New York, in the county and State of New York, have invented new and useful Improvements in Kilns for Burning Pottery-Ware and other Articles, of which the following is a specification.

This invention relates to a kiln which is composed of a circular burning-chamber, a series of fire-places arranged on the periphery of a circle below the bottom of the burning-chamber, a central flue opening into the burning-chamber, a series of radiating-flues extending from the fire-places to the central flue, a circular flue situated beneath the bottom of the burning-chamber, a series of vertical flues extending from the burning-chamber to the circular flue, and a smoke-flue leading from the circular flue to the chimney, so that the heated gases which rise from the fires in the fire-places pass through the central flue up into the burning-chamber, and after having circulated through said burning-chamber they escape through the central flue to the chimney, and thereby the articles in the burning-chamber are heated uniformly and with great economy in fuel.

With the parts above stated are further combined a series of fire-bags, one for each fire-place, and communicating with the same through vertical flues extending up close to the circular wall of the fire-chamber, and an opening in the top of said fire-chamber, which can be opened or closed by a damper for the purpose of regulating the heat in the burning-chamber.

This invention is illustrated in the accompanying drawings, in which—
Figure 1 represents a vertical central section. Fig. 2 is a horizontal section in the plane $x x$, Fig. 1. Fig. 3 is a similar section in the plane $y y$, Fig. 1. Fig. 4 is a similar section in the plane $z z$, Fig. 1.

Similar letters indicate corresponding parts. In the example shown in the drawings, the letter A designates the burning-chamber of my kiln, which is built, by preference, in a circular form, but which may be polygonal or of any other form suitable for the purpose. A door, B, gives access to the burning-chamber, and be-

low the bottom of said burning-chamber are a series of fire-places, C, which communicate, by radiating-flues a , with a central flue, b , leading up through the bottom of the burning-chamber, and below the radiating-flues a is a circular flue, c , Fig. 4, which communicates with the burning-chamber through a series of vertical flues, d , extending up between the radiating-flues, as shown in Figs. 2 and 3, and from said circular flue c extends a smoke-flue, e , to the chimney D.

From the bottom of the burning-chamber rise a series of fire-bags, E, one over each of the fire-places C, and situated close to the inner wall of the burning-chamber, as shown in Figs. 1 and 2 of the drawings. From each fire-place rises a vertical flue, f , into the corresponding fire-bag E, and in the top of the burning-chamber is an opening, g , which can be closed or opened by means of a damper, h , Fig. 1. After the articles to be burned have been placed into the burning-chamber A the door B is firmly closed and fires are started in the several fire-places C. The heated gases from the fires pass up into the burning-chambers, partly through the central flue, b , and partly through the fire-bags E, and after striking the top of the burning-chamber they are turned downward, and escape through the vertical flues d , circular flue c , and smoke-flue e . By these means the heat is uniformly distributed throughout the burning-chamber, and the articles contained therein are burned uniformly, with great economy in fuel. It must be remarked that in order to accomplish this purpose the fire-bags E and flues f might be closed or omitted, since a uniform distribution of heat in the burning-chamber will be effected by the co-operation of the radiating-flues a , central flue, b , vertical flues d , circular flue c , and smoke-flue e .

If the heat in the burning-chamber rises beyond the desired point, I open the damper h , and the heated gases pass straight up from the fire-places through the fire-bags and escape through the opening g , so that the danger of injuring the articles in the burning-chamber by overheating the same can be avoided.

What I claim as new, and desire to secure by Letters Patent, is—

1. In combination with the burning-cham-

ber, the fire-places C, flues f, central and radiating flues, the fire-bags E, located over the fire-places in close proximity to the wall of the kiln on its interior, substantially as and for the purpose specified.

2. In combination with the burning-chamber, the fire-places, central and radiating flues of a kiln, the circular flue e, located below the radiating-flues and connecting with the burning-chamber through vertical flues intermedi-

ate of the radiating-flues, substantially as and for the purpose specified.

In testimony whereof I have hereunto set my hand and seal in the presence of two subscribing witnesses.

WILLIAM FRENCH. [L. S.]
